(57) **CLAIM**

The ornamental design for a watch, as shown and described.

DESCRIPTION

FIG. 1 is a perspective view of a watch showing my new design;

FIG. 2 is a top plan view thereof;

FIG. 3 is a bottom plan view thereof;

FIG. 4 is a front elevational view thereof;

FIG. 5 is a first side elevational view thereof;

FIG. 6 is a second side elevational view thereof; and,

FIG. 7 is a rear elevational view thereof.

The structural features depicted by broken lines in FIGS. 3 through 7 have been shown for the purpose of illustrating portions of the watch that form no part of the claimed design.
